UNITED STATES PATENT OFFICE.

FRANCIS J. COLE, OF SCHENECTADY, NEW YORK.

VALVE-GEAR.

1,076,099.

Specification of Letters Patent.

Patented Oct. 21, 1913.

Application filed February 24, 1913. Serial No. 750,127.

To all whom it may concern:

Be it known that I, FRANCIS J. COLE, of Schenectady, in the county of Schenectady and State of New York, have invented a certain new and useful Improvement in Valve-Gears, of which improvement the following is a specification.

My invention relates to locomotive engine valve gears of the well known "Walschaert" type, and its object is to provide means whereby the motion of a steam distribution valve actuated by valve gear of such type may be accelerated toward the ends of its traverse in each direction, thereby resulting in prolonging the expansion and decreasing the compression of the steam as well as somewhat increasing the port opening.

The improvement claimed is hereinafter fully set forth.

20 In the accompanying drawings: Figure 1 is a side view, partly in section, of so much of a locomotive engine as illustrates an application of my invention; Fig. 2, a similar view, partly in vertical longitudinal section and on an enlarged scale, of my improved valve gear; Fig. 3, a rear view, partly in vertical transverse section, of the same; Fig. 4, a plan or top view; and, Fig. 5, a horizontal section, on the line *a a* of Fig. 2.

30 My invention is herein exemplified as applied in connection with a Walschaert valve gear which comprises, as in ordinary practice, a pivoted link, 11, coupled to one end of an eccentric rod, 11^a, the opposite end of which is coupled to a return crank, 11^b, fixed on one of the crank pins of the main driving axle; a combination link, 5, coupled to the cross head, 5^a; and a combination lever, 4, coupled to the combination link and to one 40 end of a radius rod, 6, the opposite end of which is fitted to traverse in the slot of the link, 11. The distribution valve stem, 3, is connected to an inside admission distribution valve, 3^a, and is, as usual, actuated by the combination lever, 4. The novel construction and connection of said lever with the valve stem, and radius rod, by which the results of my invention are attained, will now be described.

50 In the practice of my invention, the combination lever, 4, in lieu of being, as heretofore, positively connected to, and suspended on, the valve stem, is suspended, by a pair of links, 12, located on its opposite sides, 55 from a support, 1, fixed to the valve chest, 2, the upper ends of said links being jour-

naled on pins, 12^a, fixed in the support, 1, and their lower ends being coupled to the combination lever by a pin, 12^b. The upper end of the combination lever is coupled to the radius rod by a pin, 6^a, and a longitudinal slot, 4^a, is formed in the combination lever, below said pin, in which slot a block or die, 13, is fitted truly. The die, 13, is coupled to the cross head, 7, of the valve stem, by a pin, 13^a, the valve stem and distribution valve being thereby reciprocated by the combination lever, with the capacity of independent relative movement of the latter.

Under the construction above described, the distance between the centers of the pin connecting the radius rod with the combination lever, and of the valve stem is variable, being least at the center of the valve travel, and greatest at the ends. In operation, the effect of this construction is to accelerate the motion of the distribution valve at the ends of its traverse, giving a quicker motion and exerting a marked influence on the valve events in prolonging the expansion, 80 decreasing the compression and somewhat increasing the port opening. The characteristic comparatively sharp ended ellipse produced by the Walschaert and analogous valve gears may be changed by so proportioning the parts as to enable the events of cut off, expansion, release compression, port opening, etc., to be controlled as may be best suited for different classes of service.

I claim as my invention and desire to secure by Letters Patent:—

1. The combination, in a locomotive engine valve gear of the Walschaert type, of a distribution valve stem, and intermediate connections coupling said valve stem to the combination lever of the valve gear below the connection of the radius rod to said lever, with the capacity of movement of said lever transversely to that of the valve stem.

2. The combination, in a locomotive engine valve gear, of a link for reversing and changing the point of cut off, an eccentric rod coupled to and vibrating said link, a radius rod movable in said link, a combination lever coupled at one end to said rod, a combination link coupling the opposite end of said lever to a cross head, a distribution valve stem coupled to the combination lever, between the connections of the radius rod and the combination link thereto, and means for permitting movement of the combination lever transversely to that of the valve stem.

3. The combination, in a locomotive engine valve gear, of a pivoted link, an eccentric rod coupled thereto, a radius rod fitted to traverse in the link, a longitudinally slotted combination lever coupled to the radius rod, links suspending said combination lever from a fixed support, a distribution

valve stem, and a die fitting the slot of the combination lever and coupled to the distribution valve stem.

FRANCIS J. COLE.
